UNITED STATES PATENT OFFICE.

WILLIAM E. HOKE, OF ST. LOUIS, MISSOURI.

METHOD OF AND MACHINE FOR MAKING GAUGES AND OTHER ARTICLES.

Application filed March 13, 1920. Serial No. 365,458.

To all whom it may concern:

Be it known that I, WILLIAM E. HOKE, a citizen of the United States, residing at St. Louis, Missouri, have invented certain new and useful Improvements in Methods of and Machines for Making Gauges and Other Articles, of which the following is a specification.

This invention relates to a method which 10 is similar in some respects to the methods presented in my copending application for methods of making identical articles, Serial No. 252,073, filed Aug. 30, 1918, and in my copending application for methods of and 15 machines for making gauges and other articles, Serial No. 289,591, filed Apr. 12, 1919. In accordance with the present invention I provide certain improved features of method particularly adapted for the making 20 of gauge blocks having their opposite end faces at predetermined angles to each other and the method as concerns some of its features is limited to the making of such gauge blocks. The invention further relates to an 25 improved machine for practising the method herein set forth.

One of the objects of the present invention is to provide an improved method of lapping or reducing gauge blocks and 30 provide them with opposite flat faces at predetermined angles to each other. Another object of the invention is to provide in conjunction with the lapping method an improved method whereby the angles formed 35 may be checked and measured. A further object of the invention is to provide an improved lapping method not necessarily limited to the lapping of angle gauges and involving the application of pressure to relatively movable laps at positions in approximately fixed relation to the blocks being lapped. A still further object of the invention is to provide an improved machine 40 adapted for carrying out the features of the method last above set forth. Still further objects of the invention will be apparent from the following specification and claims.

In the accompanying drawings I have 50 illustrated diagrammatically a machine whereby the method may be practised, the said machine embodying the mechanical features of the invention. It will be under-

stood that the drawings are entirely diagrammatic in character, being intended merely to illustrate the principles of the invention. The drawings, therefore, are to be considered as being merely illustrative and are not to be construed as defining or limiting the scope of the invention the accompanying claims being relied upon for that purpose.

Of the drawings:

Figure 1 is a plan view.

Fig. 2 is a side elevation.

Fig. 3 is an end elevation.

Figs. 4, 5 and 6 are diagrammatic views illustrating various arrangements of the blocks being lapped.

Fig. 7 is a diagrammatic view illustrating 70 a method of measurement constituting a part of the invention.

Fig. 8 is a view similar to Fig. 7 but illustrating another form of the method of measurement.

Fig. 9 is a view similar to Fig. 7 but illustrating still another form of the method of measurement.

Referring particularly to Figs. 1 to 3 of the drawings, 1 and 2 are large plates or laps arranged in opposite relationship and provided respectively with adjacent flat surfaces 3 and 4. The laps may be made of cast iron or of other suitable material and the surfaces 3 and 4 are made as flat as possible in accordance with any usual or preferred method for the production of flat surfaces.

As already stated, the invention is particularly adapted for the making of angle 90 gauges or blocks having flat end surfaces with predetermined angles between them. The angle gauges or blocks are initially formed with end faces arranged at approximately the desired angle, the blocks being 95 hardened and the end faces being ground. As shown the blocks are represented by A and the opposite end faces thereof are represented by b and c. The side surfaces d-d and e-e of the blocks are preferably all 100 perpendicular to one of the end surfaces as, for instance, b and preferably the larger side faces d-d are made flat and parallel by any usual or preferred method.

In practising my improved method a 105 number of the gauge blocks A formed pre-

liminarily as aforesaid are arranged in a row with their relatively angularly disposed faces *b* and *c* approximately in the same planes respectively. The gauge blocks are placed between the two laps 1 and 2 which are adjusted angularly so that their working surfaces 3 and 4 are in engagement or approximately in engagement respectively with the relatively angularly disposed faces *b* and *c* of the blocks. The laps 1 and 2 are not rigidly held or positively guided but are free to adjust themselves angularly in accordance with the angles between the block faces and in accordance with initial variations in the blocks.

I do not limit myself as concerns the broader phases of the invention to any exact relative positioning of the gauge blocks and laps. I prefer, however, to arrange the laps vertically with the blocks in a vertical row between them. The lapping surfaces 3 and 4 are charged or otherwise coated with abrasive material and under some circumstances it is preferable to have the surfaces vertical rather than horizontal or approximately horizontal so that there will be no tendency for the larger and coarser particles of abrasive to collect on the lower lap and thus cause the lapping action at the lower lap to be different from that at the upper lap. I prefer and have illustrated an arrangement whereby the gauge blocks are held stationary or substantially so and whereby the laps are bodily moved with respect to the blocks.

For holding the blocks I provide a stationary plate 5 having an aperture into which the blocks are loosely fitted. Preferably the laps are reciprocated in opposite directions. The reciprocation may take place vertically or horizontally and I prefer to combine these two movements to avoid any possible scratching or scouring of the blocks which might take place if reciprocation were to be effected in one direction only. As illustrated, the laps are carried by a cable 6 passing over a pulley 7, the laps thus serving to counterbalance each other, and they can readily be reciprocated vertically in opposite directions manually or by some suitable power mechanism not shown. In order that the laps may be reciprocated horizontally each of them carries a vertical rod 8 which passes through a slot in a centrally pivoted lever 9. It will be seen that by rocking this lever manually or by some suitable power mechanism not shown the two laps can be reciprocated horizontally in opposite directions. The rods 8 are sufficiently long to permit the horizontal reciprocations to be effected without interfering with the vertical reciprocations. Preferably the vertical reciprocations are effected relatively rapidly and the horizontal reciprocation relatively slowly. It is particular-

ly important that the horizontal reciprocations take place oppositely because on account of the relatively angular position of the laps each of them crosses the path of the other as indicated by dot-and-dash lines in Fig. 1.

It is necessary to apply a considerable pressure between the laps and the blocks and when the laps are arranged vertically as herein shown the pressure must be applied mechanically. It is highly desirable to apply the pressure in such a way that it will be substantially uniformly distributed over the block surfaces and it is therefore desirable to have the points of application of the pressure symmetrically located with respect to the block surfaces taken as a whole. In order that this relationship may be maintained the positions at which pressure is applied must be located in approximately fixed relation to the group of blocks.

When the blocks are stationary as herein shown the places of pressure application are also stationary. As illustrated, there are two wheels 10—10 engaging the outer surface of each lap, these wheels being connected with levers 11—11 and springs 12—12 in such a way that the wheels exert a uniform pressure against the laps. The wheels have no bodily movement except such minor movements as are necessary to adjust themselves to the positions of the laps. The wheels are located approximately symmetrically with respect to the surfaces being lapped. The distribution of pressure on the block surfaces is therefore substantially the same for all positions of the laps. The arrangement of the wheels is such as to freely permit the rapid vertical reciprocations of the laps without however interfering with the slow horizontal reciprocations.

In practicing the invention the blocks after having been preliminarily formed as before stated are arranged in a row and are suitably secured in fixed relationship to each other by clamping or soldering or cementing or by wringing together the surfaces *d*—*d* or in any other suitable manner. The blocks having thus been connected together are mounted in the plate 5 between the laps 1 and 2 and the laps are reciprocated in the manner stated until the several surfaces *b*—*b* and *c*—*c* of the blocks have been reduced to the same planes. If the surfaces 3 and 4 are perfectly flat as is pre-supposed then the faces *b* and *c* of the several blocks will be not only flat but also at the same angle to each other. The faces *b* and *c* are sufficiently accurate to permit adjacent faces of different blocks to be placed or wrung together and held by the well-known adhering action of flat surfaces. However, the said faces *b* and *c* will not necessarily be perpendicular to the side surfaces *d*—*d*. In order to make the blocks absolutely iden-

- tical they are removed from between the laps and separated and the relative positions of some of the blocks are changed. This changing can be effected in different ways, 6 two such ways being illustrated in Figs. 4, 5 and 6. Fig. 4 shows a series of blocks A' to A^{12} as initially arranged in a row for the first lapping operation. Some of the blocks may be interchanged as illustrated in Fig. 5. 10 As shown, alternate blocks starting from the opposite ends of the row are transposed. Assuming that the blocks at one end of the row initially averaged somewhat larger than those at the other end it will be clear that 15 this variation would be retained to some extent after the first lapping operation. The transposing of some of the blocks as shown in Fig. 5 will place the larger and the smaller blocks in alternate relationship. 20 Another method of changing the relative positions of some of the blocks is shown in Fig. 6. In this view as illustrated, alternate blocks have been turned over so as to interchange the positions of the faces b and c . 25 After the relative positions of some of the blocks have been changed either as illustrated in Fig. 5 or as illustrated in Fig. 6 or in some other manner the blocks are again fastened together as aforesaid, care being 30 taken to get all the faces at one end positioned in the same plane. This can be done by placing the blocks on one of the laps 1 or 2 or on some other convenient flat surface so that all of the faces b or all of the faces c 35 are in engagement with the said flat surface. At the same time care should be taken to bring all of the surfaces e at one end into a common plane. The blocks having been again fastened together are restored to place between the laps and the lapping operation is repeated. The lapping and changing operations are repeated alternately until the blocks have not only identical angles but are also of the same size, with the surfaces a and c exactly perpendicular to the surfaces d and d .
- By the method as thus far described the blocks are formed with identical angles but it is by no means certain that the angles are 50 the desired or predetermined angles. It is then necessary to measure the angles and to make suitable corrections. Any errors in the angles of the blocks can be approximately corrected by hand or by repeating the lapping between the laps and applying uneven pressure. After approximate corrections have been made as before stated the lapping and changing operations are repeated as already described until identity of 55 the several angles is again attained. The angles are again measured and if an error is still found further approximate corrections are made. These operations are continued until exactly the desired angles are obtained. 60 The measuring of the angles of the blocks is preferably effected in the way illustrated in Figs. 7 to 9. It is difficult to measure the angle of a single block with accuracy particularly when there is no standard angle available which is the same as that desired 70 and even when a standard angle is available appreciable errors will occur in the measurement of any one block. I therefore prefer to measure the angles of a number of blocks arranged in multiple as shown in Fig. 7 75 When the desired angle is a divisor of 180° then a number of blocks can be placed together or built up to form a resultant angle which is supposedly 180° and which can be checked up or measured by means of an ordinary flat plate. As illustrated, the respective flat faces b and c of the several blocks are wrung together to form an angle which is supposedly 180° and this is checked 80 by attempting to ring both of the end surfaces of the series upon a flat plate such as S . If the blocks will wring to the flat plate then the observer knows that the angles of all of the blocks are exactly correct. If any error is found the observer will know 85 that this total error is a multiple of the error of each individual block and can make corrections on the individual blocks sufficient to correct the total error. By then re-lapping as aforesaid the blocks can be restored to exactly identical angles. After that the angles can again be tested and these operations can be continued until the exact predetermined angles are obtained. 90 When the desired angle is not a divisor 100 of 180° it is still possible to make use of a flat plate such as R . By first making preliminary sets of blocks such as A and B which are divisors of 180° , it is possible to use these in combination with the blocks to 105 be finally made in such a way as to build up a total angle of 180° . As illustrated in Fig. 8, there is a block A having an angle of 30° , a block B having an angle of 20° and ten blocks C^1 to C^{10} having identical angles 110 which are supposedly 13° . For convenience use may be made of a block or plate S having opposite flat parallel faces. By lapping and correcting the blocks C^1 to C^{10} so that the total angle is 180° the said blocks C^1 to C^{10} will be formed with angles of 115 exactly 13° . 120 Another method of measuring is illustrated in Fig. 9. In this case use is made of several identical blocks having an angle which is a divisor of 180° and these blocks are combined to make a resultant angle different from 180° . Then by combining another series of blocks to make an angle which is supposedly the same as that formed by 125 the first blocks and by comparing and correcting, the angle of the second blocks can be made to have the predetermined value. As illustrated in Fig. 9, there are five blocks A' to A^5 each having an angle of 30° , thus 130

making a total angle of 150°. There are six blocks D' to D⁶ each having an angle of 25°, these also making an angle of 150°. For convenience in comparing use is made of two flat plates R and T.

What I claim is:

1. The method of reducing a number of similar but not necessarily identical blocks to produce opposite flat faces at identical angles to each other which consists in arranging the several blocks in a row with their relatively angularly disposed faces approximately in the same planes respectively and in engagement or approximately in engagement respectively with two relatively angularly disposed flat laps, permitting the laps to adjust themselves angularly in accordance with the angles between the block faces and in accordance with the sizes of the blocks, causing movement between the blocks and the laps to effect lapping while maintaining the blocks arranged in a row as aforesaid, changing the relative positions of some of the blocks to distribute variations in the angles and in the sizes, and repeating the lapping and changing operations alternately until identical angles and sizes are obtained. 65
2. The method of reducing a number of similar but not necessarily identical blocks to produce opposite flat faces at identical angles to each other, which consists in arranging the several blocks in a row with their relatively angularly disposed faces approximately in the same planes and in engagement or approximately in engagement respectively with two relatively angularly disposed flat laps, permitting the laps to adjust themselves angularly in accordance with the angles between the block faces, simultaneously reciprocating the laps in two directions at an angle to each other to effect lapping while maintaining the blocks arranged in a row as aforesaid. 70
3. The method of reducing a number of similar but not necessarily identical blocks to produce opposite flat faces at identical angles to each other, which consists in arranging the several blocks in a row with their relatively angularly disposed faces approximately in the same planes and in engagement or approximately in engagement respectively with two relatively angularly disposed flat laps, permitting the laps to adjust themselves angularly in accordance with the angles between the block faces, and reciprocating the laps oppositely in the direction of the aforesaid angles to effect lapping while maintaining the blocks arranged in a row as aforesaid, each lap moving into and out of the path of movement of the other. 75
4. The method of reducing a number of similar but not necessarily identical blocks having flat side faces to produce opposite flat faces at identical angles to each other and perpendicular to the said side faces, which consists in arranging the several blocks in a row with the said side faces parallel and with their relatively angularly disposed faces approximately in the same planes and in engagement or approximately in engagement respectively with two relatively angularly disposed flat laps, permitting the laps to adjust themselves angularly in accordance with the angles between the block faces and in accordance with the sizes of the blocks, causing movement between the blocks and the laps to effect lapping while maintaining the blocks arranged in a row as aforesaid, changing the relative positions of some of the blocks in the row to distribute variations in the angles and in the sizes, positioning the blocks with all of the corresponding angle faces at one end 80
5. The method of reducing a number of similar but not necessarily identical blocks having flat side faces to produce opposite flat faces at identical angles to each other and perpendicular to the said side faces, which consists in arranging the several blocks in a row with the said side faces parallel and with their relatively angularly disposed faces approximately in the same planes and in engagement or approximately in engagement respectively with two relatively angularly disposed flat laps, permitting the laps to adjust themselves angularly in accordance with the angles between the block faces and in accordance with the sizes of the blocks, causing movement between the blocks and the laps to effect lapping while maintaining the blocks arranged in a row as aforesaid, changing the relative positions of some of the blocks by reversing them and by moving them to different positions in the row to distribute variations in the angles and in the sizes, and repeating the lapping operations alternately until identical angles and sizes are obtained. 85
6. The method of reducing a number of similar but not necessarily identical blocks having flat side faces to produce opposite flat faces at predetermined identical angles to each other and perpendicular to the said side faces, which consists in arranging the several blocks in a row with the said side faces parallel and with their relatively angularly disposed faces approximately in the same planes and in engagement or approximately in engagement respectively with two relatively angularly disposed flat laps, permitting the laps to adjust themselves angularly in accordance with the angles between the block faces and in accordance with the sizes of the blocks, causing movement between the blocks and the laps to effect lapping while maintaining the blocks arranged in a row as aforesaid, changing the relative positions of some of the blocks in the row to distribute variations in the angles and in the sizes, positioning the blocks with all of the corresponding angle faces at one end 90

cated in the same plane, and repeating the aforesaid operations in succession until identical angles and sizes are obtained.

7. The method of reducing a number of similar but not necessarily identical blocks to produce opposite flat faces at predetermined identical angles to each other, which consists in arranging the several blocks in a row with their relatively angularly disposed faces approximately in the same planes respectively and in engagement or approximately in engagement respectively with two relatively angularly disposed flat laps, permitting the laps to adjust themselves angularly in accordance with the angles between the block faces and in accordance with the sizes of the blocks, causing movement between the blocks and the laps to effect lapping while maintaining the blocks arranged in a row as aforesaid, measuring the angles between the faces, approximately correcting any error, again lapping as aforesaid, and repeating the measuring, correcting and lapping operations in succession until the predetermined identical angles are obtained.

8. The method of reducing a number of similar but not necessarily identical blocks having flat side faces to produce opposite flat faces at predetermined identical angles to each other and perpendicular to the said side faces, which consists in arranging the several blocks in a row with the said side faces parallel and with their relatively angularly disposed faces approximately in the same planes and in engagement or approximately in engagement respectively with two relatively angularly disposed flat laps, permitting the laps to adjust themselves angularly in accordance with the angles between the block faces and in accordance with the sizes of the blocks, causing movement between the blocks and the laps to effect lapping while maintaining the blocks arranged in a row as aforesaid, changing the relative positions of some of the blocks to distribute variations in the angles and in the sizes, repeating the lapping and changing operations alternately until identical angles and sizes are obtained, measuring the said angles, approximately correcting any error, and repeating the aforesaid operations in succession until the predetermined identical angles are obtained.

9. The method of making a number of similar blocks with faces at predetermined identical angles, which consists in subjecting the blocks to a reducing operation whereby they are formed with identical angles approximating the desired angles, stopping the reducing operation and placing the blocks together to build up an angle approximating a known standard angle, comparing the built-up angle with the standard angle, approximately correcting the total error if

any, and repeating the comparing, correcting and reducing operations in succession until the predetermined identical angles are exactly obtained.

10. The method of making a number of similar blocks with faces at predetermined identical angles, which consists in subjecting a preliminary number of blocks to a reducing operation whereby they are formed with identical angles different from the said predetermined angles, stopping the reducing operation and placing the blocks together to build up an angle of 180° formed by a flat plate, comparing the built-up angle with the standard angle, approximately correcting the total error if any, repeating the comparing, correcting and reducing operations in succession until known identical angles are exactly obtained, and repeating the aforesaid operations with the block to be finally made, using one or more of the said preliminary blocks to form angles for purposes of comparison.

11. The method of reducing a number of similar but not necessarily identical blocks having flat side faces to produce opposite flat faces at identical angles to each other and perpendicular to the said side faces, which consists in arranging the several blocks in a row with the said side faces parallel and with their relatively angularly disposed faces approximately in the same planes and in engagement or approximately in engagement respectively with two relatively angularly disposed flat laps, permitting the laps to adjust themselves angularly in accordance with the angles between the block faces and in accordance with the sizes of the blocks, causing movement between the blocks and the laps to effect lapping while maintaining the blocks arranged in a row as aforesaid, changing the relative positions of some of the blocks to distribute variations in the angles and in the sizes, repeating the lapping and changing operations alternately until identical angles and sizes are obtained, stopping the aforesaid reducing operations and placing the blocks together to build up an angle approximating a known standard angle, comparing the built-up angle with the standard angle, approximately correcting the total error if any, and repeating the comparing, correcting and reducing operations in succession until the predetermined identical angles are exactly obtained.

12. The method of reducing a number of similar but not necessarily identical blocks to produce opposite flat end faces in identical relation to each other, which consists in arranging the several blocks in a definite group between two opposed flat laps, permitting the laps to relatively adjust themselves in accordance with initial variations in the blocks, causing movement between the

blocks and the laps to effect lapping, and applying pressure to the laps at positions in approximately fixed relation to the group of blocks.

5 13. The method of reducing a number of similar but not necessarily identical blocks to produce opposite flat end faces in identical relation to each other, which consists in arranging the several blocks in a definite 10 group between two opposed flat laps, permitting the laps to relatively adjust themselves in accordance with initial variations in the blocks, reciprocating the laps in opposite directions with respect to the blocks 15 to effect lapping, and applying pressure to the laps at positions in approximately fixed relation to the group of blocks.

14. The method of reducing a number of similar but not necessarily identical blocks 20 to produce opposite flat end faces in identical relation to each other, which consists in arranging the several blocks in a definite group between two opposed flat vertical laps, permitting the laps to relatively adjust 25 themselves in accordance with initial variations in the blocks, causing vertical movement between the blocks and the laps to effect lapping, and applying pressure to the laps at positions in approximately fixed 30 relation to the group of blocks.

15. The method of reducing a number of similar but not necessarily identical blocks to produce opposite flat end faces in identical relation to each other, which consists in arranging the several blocks in a definite 35 group between two opposed flat laps having their lapping surfaces disposed in vertical planes, moving the laps in the lapping

planes so as to produce a rapid vertical lapping action and a relatively slower horizontal lapping action. 40

16. A lapping machine including in combination, two opposed laps having flat working surfaces and mounted for free relative angular adjustment, means for holding 45 blocks to be lapped, means for effecting relative movement between the laps and said holding means to effect lapping, and means in approximately fixed relation to said holding means for applying pressure to the laps. 50

17. A lapping machine including in combination, two opposed laps having flat working surfaces and mounted for free relative angular adjustment, means for holding blocks to be lapped, means for oppositely 55 reciprocating the laps with respect to said holding means to effect lapping, and means in approximately fixed relation to said holding means for applying pressure to the laps.

18. A lapping machine including in combination, two opposed vertical laps having flat working surfaces and mounted for free relative angular adjustment, means for holding blocks to be lapped, means for effecting composite vertical and horizontal 60 movement between the laps and said holding means to effect lapping, and means in approximately fixed relation to said holding means for applying pressure to the laps. 65

19. Lapping machine according to claim 18 including means whereby the rate of vertical movement and the rate of horizontal movement may be separately controlled. 70

In testimony whereof, I hereto affix my signature:

WILLIAM E. HOKE.
